UNITED STATES PATENT OFFICE.

LOUIS G. MERRITT, OF LOCKPORT, NEW YORK.

AUTOMATIC VENEER DRIER.

Application filed July 9, 1921. Serial No. 483,413.

To all whom it may concern:

Be it known that I, LOUIS G. MERRITT, a citizen of the United States, residing at Lockport, in the county of Niagara and 5 State of New York, have invented certain new and useful Improvements in Automatic Veneer Driers, of which the following is a full, clear, and exact description, such as will enable others skilled in the art to which 10 it appertains to make and use the same.

This invention relates to drying apparatus, and more particularly in some of its details to such apparatus for drying veneer or similar material.

15 It is an object of the invention to provide an improved apparatus of the class mentioned adapted to receive sheets of veneer or similar material for drying, and to automatically and periodically subject alternate 20 layers of the same to pressure and heat and to automatically release said pressure at intervals so as to prevent checking or splitting of the veneer.

Another object is to provide an apparatus 25 of the class mentioned having improved means for automatically and periodically applying and removing pressure from the veneer or other material subjected to treatment.

30 Another object is to provide a drying machine of the class mentioned with improved means for mounting the drying platens thereof for reciprocation.

Still another object is to provide an improved drying apparatus of the class mentioned of simple and durable construction, functioning advantageously to dry material such as veneer or the like without injury thereto, and with material saving in time 40 and labor.

Other objects will be in part obvious in connection with the following detailed description of an illustrative embodiment of the invention and will be in part pointed out in connection therewith.

In the accompanying drawing wherein an illustrative drawing for a detailed description but preferred embodiment of the invention is shown,

50 Figure 1 is a side elevation of the veneer drying apparatus embodying the invention;

Fig. 2 is an end elevation thereof;

Fig. 3 is a detailed enlarged fragmentary view showing the method of mounting the platens for oscillation; and

55

Fig. 4 is a fragmentary sectional plan showing the connection of the posts to the rocker.

Referring now to the drawing for a detailed description, the drying machine comprises a series of superposed platens 1 having spaces therebetween and arranged to be supported by posts 2 and 3, the latter being arranged in spaced pairs at opposite sides of the platens, and the whole being supported upon a base including spaced I-beams 4 connected by tie rods 5. Each of the platens is provided with laterally extending lugs 6, preferably integral therewith, adapted to engage on seats provided by the integral webs 7 formed on the posts. As shown in Fig. 3, the posts are preferably of integral cast construction and comprise side members 8 connected by the webs 7 providing openings above and below for the reception of the lugs, while stiffening webs 9 are provided adjacent the openings extending between the side members 8. The posts are provided with lower terminal formations 10 for supporting the same and connecting them to operating mechanism. Suitable cover plates 11 may be secured to the outer faces of the posts so as to present a finished appearance and to exclude dust, &c.

85

Any desired number of superposed platens spaced apart may be employed, and, as shown in Fig. 3, alternate platens, as A, are connected by lugs 6 to the posts 2 of each pair, while the other alternate platens, as B, are similarly connected to posts 3. As shown in Fig. 1, the posts 2 are connected by tie-bars 12 secured to the posts, while the posts 3 are similarly connected by tie-bars 13. It will therefore be seen that all of the posts connected to the A series of platens are secured together, while all of the posts of the B series are similarly secured together, constituting two separate frames on each side of the machine. The frames at 100 opposite sides are cross connected at the top by cross channels 14, thus forming two platen frames or units, one carrying the A-series of platens and the other carrying

the B-series, the units being movable relatively to each other, as will be more fully pointed out.

Links 14' are pivotally connected to posts 5 of the respective platen frames, as shown in Fig. 1, so as to guide the relative movement between the two frames. Spaces are provided between adjacent platens for receiving the veneer, the spaces immediately above 10 the A platens constituting one series or set, and those immediately above the B platens constituting another series.

The platens are preferably metallic and hollow, as shown, to receive steam or other 15 heat conveying medium. Each platen is preferably constructed in a plurality of sections the edges of which are provided with complementary inter-engaging projections and grooves as shown at 15, and lugs 15' 20 at the lateral edges thereof are provided for receiving bolts 16 for uniting the sections to make up the complete platen. Each end edge of the platens is provided with a shield 25 and guiding plate 17 secured thereto and having opposite inclined surfaces for deflecting the veneer into the veneer receiving spaces between the adjacent platens, thus aiding in loading the veneer into the machine.

30 Suitable piping is employed for conveying the steam to the interior of the platens, and, as shown in Figs. 1 and 2, two networks of piping are employed, one, as 18, being connected to convey steam to one set of moving platens, and the other, as 19, being similarly connected to the other set of moving platens. This piping is connected by headers 20 and 21 so as to convey steam equally to all the pipes. The networks of piping described 40 are arranged at opposite sides of the platen units, those on one side receiving the live steam for the respective units while those on the other side are for exhaust or drainage therefrom.

45 The lower ends of the posts are connected to transverse shafts 22 supported on the I-beams 4 by journal boxes or bearings 23 bolted thereto, each of these shafts extending below the lower ends of opposite pairs of posts. A collar 24 is secured on each shaft adjacent 50 each end thereof being formed to provide an enlarged journal bearing operating in the journal box 23 to support the platens and the load thereon.

55 These collars are also provided with pins 25 and 26 suitably secured thereto and disposed on opposite sides of the center line of the shaft. These pins extend through the lower terminals of the respective posts as shown in Fig. 4. The outer ends of the pins 25 and 26 also extend through and are connected to a crank plate or rocker 27 having upwardly and downwardly extending arms. It will be understood that this construction for supporting the platens is dis-

posed adjacent the lower ends of each pair of posts at both sides of the machine.

An operating shaft 28 extends across the machine, being mounted in suitable bearings 28' on the I-beams 4, and at each end thereof 70 is mounted a double ended rocker arm 29 pivotally connected at its upper end to a link connection 30 and at its lower end in a similar link connection 31, each link being pivotally connected respectively with the upper and lower crank arms of the crank plates 27 as shown in Figs. 1 and 3. Bolted to the rocker arm 29 is a crank lever 32 and pivotally connected to the upper extremity of the latter is a pitman bar 33 pivotally connected at its opposite end to the slide 34 of an adjustable crank arm 35. It will be understood that the construction just described for oscillating the platens is duplicated at opposite sides of the machine so that operating and load stresses are equalized, and warping, undue friction and wear are avoided. The pitmen 33 are connected for reciprocation to the cranks 35 mounted at opposite ends of a transverse shaft 36 supported by the I-beams 4 and connected for continuous rotation to a motor 37 through suitable reduction gearing 38. It is to be noted that the motor is mounted beneath one end of the machine so as to be out of the way while 95 being protected and conveniently accessible for repairs, and operating torque is transmitted equally to the operating mechanism at both sides of the machine. It will be observed that the lower terminals of the posts 100 of each pair are connected at points equidistant from the center of supporting shafts 22, the A series of platens with load and attachments being thus balanced against the B series, so that under normal conditions 105 very little power is required for moving the platens from one position to another. However, when upward movement of one series is of sufficient extent to cause it to engage with the other series by contact through the 110 veneer in the spaces with the lower surfaces of the platens thereof, lifting the lugs 6 of the latter series from their supports in the posts considerable power will be required. Even with the machine heavily loaded with 115 veneer, this lifting of one series of platens occurs over a relatively short period of time and the power consumed is not great.

The details of construction having been pointed out, a cycle in the operation of the 120 machine is substantially as follows:

The parts being in the positions shown in Fig. 1, all of the spaces between the platens of the A series and the platens of the B series are loaded with veneer or the like by insertion at the ends of the machine; or one set of series of spaces may be loaded while the opposite set is closed, thus giving more room for loading. In the latter case the second series of spaces will be loaded after the plat- 130

ens are reversed by starting the operating mechanism and stopping the same as soon as the spaces are opened. Steam having been admitted to the platens, and both sets of spaces loaded, the motor 37 is started, whereupon the platens of one series, say, the A series, are carried upwardly by upward movement of posts 2 caused by clockwise rotation of the crank plates 27, as viewed in Fig. 1. At the same time the platens of the B series are lowered closing the spaces immediately above the A platens or diminishing the size thereof. The upwardly moving platens soon contact through the veneer carried on their upper surfaces with the lower surfaces of the lowering platens, lifting the latter from their post seats 7 supporting the lugs 6 of the platens. The vertical dimensions of the openings in the post above the web 7 are sufficient to permit considerable upward movement of the platens.

This action transfers the weight of the lifted platens from their trunnions to the veneer supported on the platens immediately below. During this period the veneer in one series of spaces is subjected to drying heat from platens above and below, and at the same time pressure is applied by the weight of the platens carried thereon, preventing warping. This condition must not continue too long, however, or else checking or splitting of the veneer would ensue due to pressure on the veneer when shrinkage begins to take place. The continued operation of the motor, however, soon relieves the pressure on the veneer in one series of spaces and transfers it to the veneer in the other set or series of spaces, the B series in this case rising and the A series lowering, as will be obvious. As this reversal of the platens takes place, the spaces in which heat and pressure have just been applied increase in volume causing air to rush in and circulate around the veneer and permitting the vapor and moisture to escape. When the platens again move together the air and vapor are expelled. The automatic continuance of this cycle gives rise to a "breathing" effect, causing a rapid drying in a satisfactory manner without resultant splitting or warping of the veneer and without other injurious effect thereupon.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein de-

scribed, and all statements of the scope of the invention which, as a matter of language might be said to fall therebetween.

Having described my invention, what I claim as new and desire to secure by Letters Patent, is:—

1. In a veneer drying apparatus, in combination, a plurality of platens, means for connecting said platens to form a plurality of relatively movable platen units with the platens arranged in alternate relationship forming two sets of spaces between adjacent platens for the reception of the veneer, automatic means for periodically raising and lowering said units to alternately subject the veneer in each of the series of spaces to pressure and subsequently to relieve the same, and means arranged in said connecting means to allow individual adjustment of the platens of each unit in their supports to compensate for varying thicknesses of veneer in the spaces.

2. In a veneer drying apparatus, in combination, a plurality of platens, means for connecting said platens to form a plurality of relatively movable platen units with their platens arranged in alternate relationship, rotary bearings for supporting said units adjacent opposite sides thereof, a motor driven shaft supported transversely of said units having crank arms secured at opposite ends thereof, means for connecting said crank arms and bearings at opposite sides of said units for vibrating the units in alternate relationship, and means for varying the amplitude of vibration of said units.

3. In a veneer drying apparatus, in combination, a plurality of platens, means for connecting said platens to form a plurality of relatively movable platen units with their platens arranged in alternate relationship providing two sets of spaces positioned between the adjacent platens for the reception of the material, rotary bearings for supporting said units disposed adjacent opposite sides thereof, pivoted levers at opposite sides of said units, links connecting said levers to said bearings, a motor driven shaft supported transversely of said units having crank arms secured at opposite ends thereof, means for connecting said crank arms and levers at opposite sides of said units for vibrating the units in alternate relationship, and means for varying the amplitude of vibration of said units.

4. In a veneer drying apparatus, in combination, a plurality of platens, means for connecting said platens to form a plurality of relatively movable platen units with their platens arranged in alternate relationship providing two sets of spaces between adjacent platens for the reception of the material, rotary bearings for supporting said units disposed at opposite sides thereof, pivoted levers at opposite sides of said units,

links connecting said levers to said bearings, means for operating said levers for vibrating said units to effect alternate pressure on the material in each set of spaces, and means for varying the amplitude of vibration of said units.

5. In a veneer drying apparatus, in combination, a plurality of superposed platens, means for connecting said platens to form two relatively movable platen units, two sets of veneer receiving spaces being thus provided between adjacent platens of the two platen units, automatic means for moving one platen unit to cause the platens thereof 10 to intermittently press the veneer in one set of spaces against the platens of the other platen unit, said automatic means acting alternately also to intermittently move said other platen unit to cause the platens thereof 15 to press the veneer in the other set of spaces against the platens of said one platen unit, and means arranged in said connecting 20 means to allow individual adjustment of the platens of each unit in their supports to compensate for varying thicknesses of veneer in 25 the spaces.

6. In a veneer drying apparatus, in combination, a plurality of superposed platens, means for connecting said platens to form two relatively movable platen units, two sets 30 of veneer receiving spaces being thus provided between adjacent platens of the two platen units, automatic means for moving one platen unit to cause the platens thereof 35 to intermittently press the veneer in one set of spaces against the platens of the other platen unit, said automatic means acting alternately also to intermittently move said other platen unit to cause the platens thereof 40 to press the veneer in the other set of spaces against the platens of said one platen unit, and means for intermittently and alternately 45 relieving the pressure on the veneer in both of said sets of spaces and causing the air to circulate around the treated material, and means arranged in said connecting means to allow individual adjustment of the platens of each unit in their supports to compensate 50 for varying thicknesses of veneer in the spaces.

7. In a veneer drying apparatus, in combination, a plurality of superposed platens, means for connecting said platens to form two relatively movable platen units, two sets 55 of veneer receiving spaces being thus provided between adjacent platens of the two platen units, bearings for supporting said

platens units adjacent opposite sides thereof, crank arms operatively connected to said bearings, pitman bars connected to said 60 crank arms, and means to oscillate said pitman bars for automatically and intermittently causing compression and subsequent release of said compression on the veneer in each set of veneer receiving spaces, said last 65 mentioned means operating to effect alternate action upon the veneer in each set of spaces.

8. In a veneer drying machine, in combination, a movably mounted drying platen, 70 a second drying platen mounted for cooperation with said movable platen, driving connections for said movable platen connected thereto at opposite sides thereof and being disposed at opposite sides of the machine, 75 a motor driven shaft extending transversely of said platens and operating connections between said driving shaft and each of said driving connections.

9. In a veneer drying machine, in combination, a plurality of sets of movable platens, connections for moving said platens disposed at opposite sides thereof, a motor driven shaft extending transversely of said 80 platens, and driving connections between said shaft and each of said first mentioned connections.

10. In a veneer drying machine, in combination, a plurality of movably mounted drying platens connected to form a platen unit, a plurality of drying platens mounted to form a second platen unit and cooperating with said movable platens, rotary bearings for supporting said movable platens disposed at opposite sides thereof, pivoted 95 levers at opposite sides of said units, links connecting said levers to said bearings, a motor driven shaft extending transversely of said platens, and operating connections between said driven shaft and each of said 100 pivoted levers.

11. In a drying apparatus, in combination, spaced platens, adjacent supporting posts for said platens, a transversely extending shaft, an enlarged bearing on said shaft, a 105 crank arm upon said shaft, and pins extending between said bearing and said crank arm to connect said posts to said shaft.

In testimony whereof I affix my signature, in the presence of two witnesses.

LOUIS G. MERRITT.
